(57) CLAIM

The ornamental design for a barbecue utensil set, as shown and described.

DESCRIPTION

FIG. 1 is a front view of the barbecue utensil set showing my new design, the fork attachment being shown.

FIG. 2 is a left side view of FIG. 1, the right side view being a mirror image.

FIG. 3 is a rear view of FIG. 1.

FIG. 4 is a top plan view of FIG. 1.

FIG. 5 is a bottom plan view of FIG. 1.

FIG. 6 is a front view of the barbecue utensil with the spatula attachment being shown.

FIG. 7 is a left side view of FIG. 6, the right side view being a mirror image.

FIG. 8 is a rear view of FIG. 6.

FIG. 9 is a top plan view of FIG. 6.

FIG. 10 is a bottom plan view of FIG. 6.

FIG. 11 is a front view of the barbecue utensil with the brush attachment being shown.

FIG. 12 is a left side view of FIG. 11, the right side view being a mirror image.

FIG. 13 is a rear view of FIG. 11.

FIG. 14 is a top plan view of FIG. 11; and,

FIG. 15 is a bottom plan view of FIG. 11.

The pieces of the barbecue utensil set are shown separately for clarity of illustration.
